OTHER PUBLICATIONS"List of Convex Uniform Tilings", from web page http://en.wikipedia.org/wiki/List_of_uniform_tilings posted at least as early as Oct. 12, 2005.*Primary Examiner* — Karen S Acker*(74) Attorney, Agent, or Firm* — Laura L. Bozek(57) **CLAIM**

The ornamental design for a paper product, as shown and described.

DESCRIPTION

The sole FIGURE is a top plan view of a paper product. The outer perimeter of broken lines defines the boundaries of the paper product and forms no part thereof. The paper product is flat and planar. Thickness forms no part of the claimed design.
